UNITED STATES PATENT OFFICE.

JOHN J. CHAPIN, OF DETROIT, MICHIGAN, ASSIGNOR TO BURROUGHS ADDING MACHINE COMPANY, OF DETROIT, MICHIGAN, A CORPORATION OF MICHIGAN.

TYPE-WRITER CARRIAGE MECHANISM.

1,139,102.

Specification of Letters Patent. Patented May 11, 1915.

Application filed September 2, 1908. Serial No. 451,366.

To all whom it may concern:

Be it known that I, JOHN J. CHAPIN, a citizen of the United States, residing at Detroit, in the county of Wayne and State of Michigan, have invented certain new and useful Improvements in Type-Writer Carriage Mechanism, of which the following is a specification.

The present invention relates more particularly to the mechanism of a typewriting machine having to do with traverse of the paper carriage to and fro and one object is to put such carriage under better control when the same is shifted by hand, reducing any liability of such carriage getting away from the operator when released. Thus the invention provides for putting the release devices under control of a handle piece whose manipulation requires that the operator shall have his hand interposed in the path of some part of the carriage.

Another object of the invention is to provide an improved mounting of the carriage which will facilitate adjustment for securing a correct position of the platen at all times and will also reduce to the minimum any distortion of imprints due to slight irregularities in the carriage track.

The invention also aims to provide an improved construction for adjusting the tension of the carriage spring.

With these and incidental objects in view the invention consists in certain novel features of construction and combinations of parts the essential elements whereof are recited in the appended claims and a preferred form of embodiment of which is illustrated in detail in the accompanying drawings and specifically described herein-after.

Of said drawings Figure 1 represents a fragmentary top plan view of a typewriting machine having the improvements of the present invention; Fig. 2 represents a portion of the machine in rear elevation; Fig. 3 represents a section on the line 3-3 of Fig. 1; Fig. 4 is a fragmentary sectionalized right side elevation of the carriage; Fig. 5 is a fragmentary sectionalized top plan view; Fig. 6 is a section on line 6-6 of Fig. 5; Fig. 7 represents the right-hand end portion of the carriage in perspective with a modified construction; Fig. 8 is a sectionalized front elevation of the spring

drum for impelling the carriage together with gearing operated thereby; Fig. 9 is a section on the line 9-9 of Fig. 7; and Fig. 10 is a rear elevation of the spring drum and connected parts.

In said drawings the reference numeral 2 designates the rectangular frame of the carriage and 3 and 4 the front and back way-rods respectively on which the carriage travels. Centrally located on the front bar of this frame is a flat-tread roller 5 traveling on top of said rod 3. In the back part of the carriage frame there are mounted two grooved rollers 6 engaging the rod 4 and spaced a distance apart practically equal to the distance each is spaced from the front roller 5. The carriage thus rests on three points upon the way-rods. Lines drawn between these points would produce an equilateral triangle. The center of gravity of the carriage lies within this triangle at all times and the arrangement insures a smooth and easy travel of the carriage. Furthermore, the platen 7 being located centrally between the front and back parts of the carriage any irregularities in the way-rods which might cause a slight variance in the surface presented to the type will be so far minimized as to render the inexactness of the imprint practically imperceptible. In this connection it should be noted that the carriage is constructed for use in a typewriting machine of the so-called front strike character.

The mounting of the rear rollers 6 provides for accurate adjustment of the carriage so as to secure the proper location of the platen. The rear part of the carriage frame is formed with hanger portions 8 through opposite sides of which are entered screw plugs 9. The rear one of these screw plugs has a smooth bore whereas the front plug has a tapped bore. A bearing for the roller is introduced through the rear plug and screwed into the front plug, this bearing being in the form of an elongated pin 10 with enlarged portions 10 on which the roller turns, a centrally reduced portion 11, and a reduced front end portion 12 which is screw-threaded to engage the front plug. The hub of the pulley abuts the confronting ends of the screw plugs. It will be obvious that by adjusting the screw plugs the pulley can be shifted or rather the carriage

frame shifted with reference to the pulley and thus an accurate adjustment of the platen obtained.

The back way-rod 4 seats in semi-circular 5 sockets 14 of the frame of the machine and is grooved from end to end in the rear side just above these sockets as shown at 4^a in Fig. 2. On the rear part of the carriage frame plates 16 are secured around the 10 hanger portions 8, said plates having forwardly bent lower ends forming retaining flanges 17 to run in the groove 15 (4^a). It will be noted that this construction provides for a full traverse of the carriage from one 15 end to the other of the rod 4 without any limitation on account of the connection with the supporting frame-work. At the front the carriage is kept down on the way-rod by reason of the projection of a finger 18 on 20 the carriage under a fixed scale plate 19 as shown in Fig. 3.

The carriage is drawn to the left by a coiled spring 20 contained within a barrel or drum 21, (Figs. 8 and 9) the latter being connected by a tape 22 with the right-hand end of the carriage. Said drum is loosely mounted upon a tubular shaft 23 having an enlargement at the inner end to which the inner end of the spring 20 is 30 fastened. The outer end of said spring is engaged with a pin or stud 24 (Fig. 8) projecting from one side of the drum. A reduced portion of the shaft 23 is screw-threaded to receive an interiorly threaded 35 sleeve 26, a worm gear 27 and a lock nut 28 as shown in Fig. 9, the worm gear having holes to receive projections on said sleeve. The latter is journaled in a supporting bracket 30 and flanged at its inner end to overlie ball bearings between the 40 shaft 23 and the drum 21. Said ball bearings comprise oppositely arranged cones 31 fitting on a reduced portion of the shaft 23, balls 32 and a V-grooved ring 33 carried by 45 the drum.

It will be obvious that the tension of the spring can be varied by turning the worm gear wheel 27. Mounted in suitable bearings in the bracket 30 and a supplemental 50 bracket 34 is a short vertical shaft 35 (Fig. 10) carrying a worm 36 in mesh with said worm wheel. Said shaft is equipped with a knob 37 by which to turn it as also shown in Fig. 10. It will be seen that this construction provides an easily operated spring 55 tensioning means. By simply turning the knob 37 the spring can either be tightened or loosened to any degree.

The drum 21 carries a ratchet wheel 38 60 which engages a pawl 39 on a large gear wheel 40, the latter being loose on a journal bearing carried by the drum and meshing with a smaller gear wheel 41 carrying a worm 42 to drive ribbon feed mechanism (not shown). A gravity dog 43 engaging

the small gear wheel 41 prevents retrograde movement thereof.

Movement of the carriage under the impulse of its spring is as usual regulated by an escapement mechanism, the details of which need not here be enumerated. Suffice it to say that such mechanism comprises a rack 50 normally engaging a pinion 51 and movable up and down to disengage and reengage said pinion. This rack is carried by arms 52 pivotally mounted on opposite ends of the carriage, one of which arms appears in Fig. 1,—the arms and rack bar forming a bail. The pivot pin 53 to which this arm is secured projects through the carriage frame and there is secured to it an upstanding arm 54 connected by a spring 55 with the carriage frame, which spring acts to hold the rack down. There is loosely mounted upon said pivot pin 53 on the outer side of the arm 54 a lever 56 which extends upward and then forward alongside the carriage frame to a point near the front where it is provided with a finger piece or handle 57. This lever has a pin 58 which projects 90 behind a vertical shoulder 54^a on the upstanding arm 54. It will be obvious that depression of the lever 56 will result in a lifting of the rack by reason of the action of this pin 58 against said shoulder. At 95 the same time it will be seen that the rack can be lifted independently of the lever as in the case of tabulating through manipulation of a special key or keys. The lever 56 works up and down in a suitable guide 100 59 secured to the carriage frame and is apertured to receive the laterally turned end 60 of a locking lever 61 located under the side flange of the carriage frame and jointed to a slide rod 62 mounted in a boss 105 66 formed on the underside of the front flange of the carriage frame, the latter being finished on the upper side as a slide-way for a horn 63 connected by a pin 64 with said slide rod, the pin passing through 110 a slot in the carriage frame flange E. A spiral spring 65 connects the latter with the carriage frame, operating to normally interlock the lever 61 with the lever 56. It will be obvious that in order to depress the 115 latter lever and lift the rack it will be necessary to first operate the lever 61 so as to unlock the lever 56. To move the lever 61 it is necessary to apply pressure to the horn 63 in a direction opposite that 120 in which the carriage is moved by its spring. The horn serves as a hand-hold for moving the carriage back to the right. The relative location of the horn 63 and finger piece 57 is such that with the thumb applied to the 125 former a finger of the same hand can readily be applied to the finger piece 57. Thus the user will of necessity, when releasing the rack, have hold of the carriage in such manner as to preclude a jumping to the 130

left of said carriage upon the lifting of the rack and with the rack lifted the carriage is at all times under complete control of the user.

- 5 In the modified construction shown in Fig. 7, the rack-lifting lever 56' is formed with an up-standing lip 60' apertured to receive the laterally-turned end of a locking lever 61' pivoted intermediate its ends 10 on top of the carriage at the right-hand side thereof. This lever at its forward end is jointed to a short rod 62' which slides through a horn 63' formed on the top of the front part of the carriage frame and 15 serving as a hand-hold for moving the carriage back to the right. The rod 62' carries a thumb piece 64' in front of the concave part of said horn and similarly concaved. A spring 65' on said rod behind said thumb 20 piece thrusts the rod to the left keeping the lever 61' engaged with the lever 56'. It will be obvious that this modified construction serves a similar purpose to the construction first described, for in order to unlock the rack-lifting lever it is necessary for the operator to apply a finger or thumb to the head 64' in front of the horn 63' and move the said head in a direction opposite that in which the carriage is moved by its 25 spring and thus the operator necessarily gains a hold on the carriage as a pre-requisite to release of the same, which hold will prevent any jumping of the carriage upon the lifting of the rack.
- 30 35 It will now be seen that the above-described constructions are well calculated to fulfil the objects primarily stated although it is to be understood that such constructions are susceptible of modification within the scope of the invention.

What I claim is:

1. In a machine of the class described, the combination with a laterally movable spring-drawn paper carriage and means for holding it at different positions; of normally locked manipulative means for releasing the carriage; and an unlocking device operable in the opposite direction to that in which the carriage is moved by its spring.
- 45 50 55 60 65 2. In a machine of the class described, the combination with a laterally movable spring-drawn paper carriage and means for holding it at different positions; of means for releasing the carriage including a handle lever on one end thereof; and a lock for said lever with a handle movable in the opposite direction to that in which the carriage is moved by its spring.
3. In a machine of the class described, the combination with a laterally movable spring-drawn paper carriage and means for holding it at different positions; of means for releasing the carriage including a handle lever on one end thereof, a locking lever engaging said handle lever; and a slide piece

connected to said locking lever and movable in the opposite direction to that in which the carriage is moved by its spring.

4. In a machine of the class described, the combination with a laterally movable spring-drawn paper carriage and means for holding it at different positions; of means for releasing the carriage including a handle lever on one end thereof, a locking lever engaging said handle lever; and a handle piece slidingly mounted on the carriage to a limited extent and connected to said locking lever for disengaging the same from the handle lever by movement of the handle piece oppositely to the direction in which the carriage is moved by its spring.

5. In a machine of the class described, the combination with a laterally movable spring-drawn paper carriage and means for holding it at different positions including a member pivotally mounted on the carriage to swing up and down; of a handle lever having a one-way connection with said member for lifting it to release the carriage; and manipulative means normally locking said handle lever.

6. In a machine of the class described, the combination with a laterally movable spring-drawn paper carriage and means for holding it at different positions including a member pivotally mounted on the carriage to swing up and down; of a radial arm secured to said member; a handle lever pivoted concentrically with the latter and having a stud engaging said radial arm; and manipulative means normally locking the said handle lever.

7. In a machine of the class described, the combination of a spring-drawn paper carriage; escapement mechanism including a rack swung in the carriage; a radial arm secured to said rack; a handle lever pivoted on the end of the carriage concentrically with the rack and engaging said radial arm; a locking lever pivoted on the carriage adjacent said handle lever and normally engaged therewith; and a spring-actuated slide piece on the front of the carriage connected to said locking lever and having a handle by which it may be moved to disengage the latter from the handle lever; substantially as and for the purpose described.

8. In a machine of the class described, the combination of a supporting frame-work; a way-rod secured thereon and longitudinally grooved; and a paper carriage having rollers confined to journal bearings and running on said way-rod, said carriage having guard clips each secured at opposite sides of the journal bearings of a roller and engaging the groove in the rod at a point directly below such roller.

9. In a machine of the class described, the combination of a supporting frame with front and rear way-rods, and a carriage

5 mounted thereon having a cylindrical roller
engaging the upper surface of the front rod,
and grooved rollers engaging the upper surface
of the rear rod with provisions for ad-
justment of the grooved rollers axially with
respect to the carriage and for retaining
them at different adjustments.

10. In a machine of the class described,
the combination of a rail rod, a carriage
frame having a roller hanger portion with
screw-threaded openings at opposite sides,
screw plugs engaging said openings, a roller
whose hub abuts the confronting ends of
said screw plugs, and a journal rod entered
15 through one of the latter and screwing into
the other.

11. In a machine of the class described,
the combination of a supporting frame, a
way-rod secured therein and longitudinally
20 grooved, a carriage having a roller journaled
thereon adapted to roll upon the said way-
rod, means for adjusting the journals of the
roller axially, a clip on the carriage and
rigid therewith and engaging the groove in
25 the way-rod adjacent the roller.

12. In a machine of the class described,
the combination of a way-rod having a lon-
gitudinal groove therein, a carriage having
a grooved roller engaging the way-rod,

30 screw plugs arranged in a frame of the car-
riage on opposite sides of the roller, a jour-
nal for the roller longitudinally adjustable
in the screw plugs, and a clip extending
35 from the carriage frame into the groove of
the way-rod at a point immediately beneath
the roller.

13. In a machine of the class described,
the combination with a laterally movable
spring-drawn paper carriage, a rack there-
40 on, feeding means normally engaging the
rack, a lever on the carriage controlling the
engagement of the rack and feeding means,
and a lock for said controlling device, com-
prising a finger piece movable transversely
45 of the plane of movement of said lever.

14. In a machine of the class described,
the combination with a laterally movable
spring-drawn paper carriage, a rack there-
50 on, feeding means normally engaging the
rack, a device on the carriage controlling the
engagement of the rack and feeding means,
a lock for said controlling device, and han-
dles for the controlling device and lock re-
spectively in close relation to each other.

JOHN J. CHAPIN.
